US0D1011351S

(12) **United States Design Patent** (10) **Patent No.:** **US D1,011,351 S**
(45) **Date of Patent:** **** Jan. 16, 2024**

(54) **DOCKING STATION**

(71) Applicant: **Gang Wang**, Guangdong (CN)

(72) Inventor: **Gang Wang**, Guangdong (CN)

(**) Term: **15 Years**

(21) Appl. No.: **29/877,390**

(22) Filed: **Jun. 6, 2023**

(30) **Foreign Application Priority Data**

Dec. 17, 2022 (CN) 202230845172.4

(51) **LOC (14) Cl.** **14-02**

(52) **U.S. Cl.**

USPC **D14/433**; D14/385; D14/434

(58) **Field of Classification Search**

USPC D14/356, 357, 383, 385, 432, 433, 434, D14/435, 435.1, 436, 437, 438, 474, D14/480.1, 480.3, 480.5, 217, 171; D13/107, 108, 123, 133

CPC G06F 1/1632; G06F 13/00; G06F 13/38; G06F 13/382; G06F 13/385; G06F 13/387; G06F 9/541; G06F 2212/2146; G06F 2213/38; G06F 2213/3804; G06F 2213/3812; G06F 2213/3852; G06F 2213/40; G06F 2213/4002; G06F 2213/4004; G06K 7/0013; G06K 19/07732; G06K 19/07741; H01R 31/06

Primary Examiner — Marie D. Fast Horse

(57) **CLAIM**

The ornamental design for a docking station, as shown and described.

DESCRIPTION

FIG. 1 is a first front perspective view of a docking station showing my new design.

FIG. 2 is a second front perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines in the drawings depict portions of the docking station that form no part of the claimed design.

1 Claim, 8 Drawing Sheets
